No. 642,295.

Patented Jan. 30, 1900.

J. R. CARDWELL.

BRAKE SHOE.

(Application filed Mar. 20, 1899.)

(No Model.)

UNITED STATES PATENT OFFICE.

JAMES R. CARDWELL, OF CHICAGO, ILLINOIS.

BRAKE-SHOE.

SPECIFICATION forming part of Letters Patent No. 642,295, dated January 30, 1900.

Application filed March 20, 1899. Serial No. 709,774. (No model.)

To all whom it may concern:

Be it known that I, JAMES R. CARDWELL, a citizen of the United States, and a resident of Chicago, county of Cook, and State of Illinois, 5 have invented certain new and useful Improvements in Brake-Shoes, of which the following, taken in connection with the accompanying drawings, is a specification.

The first of the objects of my invention is 10 the provision of a hard-metal insert-plate for brake-shoes having cells extending inwardly from its face, the end walls of the cells being oblique to the face of the plate.

Another object of my invention is the construction of a cast-metal shoe provided with 15 two cellular insert-plates each of which upon one side of the face of the shoe extends for some distance past the center of the shoe. In combination with this arrangement I prefer 20 to employ the fastening-lug arranged back of the middle portion of the shoe, so that the same lug may serve as a strengthening rib or part of the casting.

Another object of my invention is the provision of a brake-shoe insert formed of a cellular plate of a depth or thickness approximately equal to the thickness of the shoe, the 25 holes in said plate being arranged obliquely with reference to the face of the shoe and 30 with reference to the radial line of the wheel against which the shoe bears. In order to get the best effect, I prefer to use a plate somewhat resembling an elongated honeycomb in structure, as the honeycomb form 35 disposes the metal to the best advantage, giving the greatest strength with least weight of material, and the elongated form of the cells or holes allows the softer metal which surrounds and incases the insert a better chance 40 to act upon the tread of the wheel.

The above, as well as such other objects as may hereinafter appear, I attain by means of a construction which I have illustrated in preferred form in the accompanying drawings, 45 in which—

Figure 1 represents part of a car-wheel having my improved brake-shoe applied thereto. Fig. 2 is a face view of the shoe. Fig. 3 is a section on the line 3 3 of Fig. 2. Fig. 4 shows 50 two of the insert-plates which I employ. Fig. 5 shows a modification of my invention in which a single insert-plate is used. Fig. 6 is

another modification, showing one of the insert-plates, in which round cells are substituted for those of honeycomb shape shown in 55 the other views of the drawings; and Fig. 7 is a section on the line 7 7 of Fig. 6.

In the practice of my invention I first construct a cellular insert-plate 8, made preferably of cast hardened metal, such as is shown 60 in Fig. 4, the outside of this plate being formed so that one can be put in each end of the brake-shoe, with the inner ends of the two extending past each other and past the center of the shoe, as clearly shown in Fig. 2. 65 Any weakness caused by the use of the two plates in the manner shown will be compensated for by the strengthening-rib 9, (shown in Fig. 1,) this rib being made large and arranged near or at the middle of the shoe. 70

Brake-shoes have been made heretofore with inserts of expanded or perforated sheet metal, and I desire, therefore, that it be understood that the terms "cell," "cellular," and "honeycomb," which I employ, are not 75 intended to cover such forms, but are used as the most suitable words I can find to distinguish my invention from such prior constructions.

In Fig. 1 I have indicated by an arrow one 80 direction of rotation of the wheel. In forming the cells 10 in the insert I arrange them so that they will stand obliquely to the face of the shoe, and also, of course, obliquely to a radial line extended out from the center 85 of the wheel. By this arrangement I secure, as at the points marked 11, a plurality of cutting or dressing edges of the hard metal, which act to better advantage in dressing the wheel and also serve the purpose of holding 90 in the ground particles of the soft metal of the shoe between the adjacent walls of each of the cells.

In Figs. 2, 4, and 5 the openings in the insert-plate are shown as being formed of what 95 may properly be called an "elongated honeycomb shape." This particular formation presents a large number of diagonal trimming edges 12, as well as a number of transverse cutting edges 13, and the bearing-point of 100 both of these edges against the periphery of the wheel is constantly shifting in position because of the obliquity of the openings 10. For example, when the shoe has worn down

to a thickness indicated by the dotted line 14, Fig. 3, the edge of the insert on the face of the shoe, which I have marked 15, will have been moved over to the place marked 16. 5 The purpose of elongating the cells is to give the soft metal which fills the cells and surrounds the insert a better chance to act upon the face of the wheel.

While the construction which is illustrated 10 in Figs. 2, 3, and 4 is that which I prefer, it is obvious that at least some of the advantages which I aim to obtain by means of my invention may be obtained by the use of a single insert-plate formed with oblique cells 15 such as I have described, and such a construction I have indicated in Fig. 5. It is also obvious that some of the advantages of my invention could be obtained even though the shape of the cells in the insert-plate were materially altered. For example, they may be 20 made cylindrical or round, as shown in Figs. 6 and 7. There are many changes in detail which may be made without departing materially from the spirit of my invention, and 25 I desire to be understood as including all such immaterial alterations as clearly within the scope of my claims.

Having thus described my invention, what I claim as new, and desire to secure by Letters 30 Patent, is--

1. A cellular brake-shoe insert-plate having the walls of the cells thereof arranged obliquely with reference to the face of the shoe.
2. A cellular brake-shoe insert-plate having 35 the walls of the cells thereof arranged obliquely with reference to the face of the shoe, the obliquity extending longitudinally.
3. A brake-shoe comprising a cast-metal body having embedded therein a cellular in-

sert-plate, the openings whereof are arranged 40 in a longitudinal oblique direction with reference to the face of the shoe.

4. A brake-shoe comprising a cast-metal body having embedded therein a cellular honeycomb-shaped insert-plate, the openings 45 whereof are arranged in a longitudinal oblique direction with reference to the face of the shoe.

5. A brake-shoe comprising a cast-metal body having embedded therein a cellular elongated honeycomb - shaped insert-plate, the 50 openings whereof are arranged in a longitudinal oblique direction with reference to the face of the shoe.

6. A brake-shoe containing two cellular 55 insert-plates each of which extends at one side of the face of the shoe for some distance past the center.

7. A brake-shoe containing two cellular insert-plates each of which extends at one side 60 of the face of the shoe for some distance past the center, and a strengthening-lug opposite the point of division between the two insert-plates.

8. A hard-metal insert-plate for brake-shoes 65 having cells extending inwardly from its face, the end walls of the cells being oblique to the face of the plate.

9. A brake-shoe comprising a cast-metal body having embedded therein a hard-metal 70 insert-plate having cells extending inwardly from its face, the end walls of the cells being oblique to the face of the plate.

JAMES R. CARDWELL.
